MORTISE CYLINDER LOCK

Harold Machinist, Sunnyside, N. Y., assignor to
Dudley Lock Corporation, Chicago, Ill., a corporation of Illinois

Application July 26, 1935, Serial No. 33,251
Renewed May 18, 1937

3 Claims. (Cl. 70—370)

The present invention relates to locks and, more particularly, to pin tumbler cylinder locks.

Cylinder locks are secured to doors or other closures in such manner that the unauthorized or surreptitious removal of the cylinders, containing the pin tumblers and the key plugs, can be accomplished with little difficulty, and once a cylinder is removed from the closure it is a very simple matter to disassemble it and by measuring the tumblers and master pins, a master key for the system from which the cylinder has been taken can be easily provided. In this manner unlawful or unauthorized entrance can be obtained to all of the rooms of an apartment house, hotel, or office building provided with locks of a master system. Furthermore, it is possible for any tenant to remove the cylinder and then hire a locksmith to change the pin tumbler combination of his lock, thereby to prevent his lock from being opened by the master key.

The object of the present invention, therefore, is to prevent the unauthorized or surreptitious removal of cylinder locks from closures provided therewith.

A further object of the invention is to prevent the removal of cylinder locks from their closures, except by a special key provided for that purpose.

Another object of the invention is to provide a cylinder lock with means to prevent the unauthorized removal of the lock from the closures, comprising interlocking means on the cylinder and on the closure, respectively, and key-operated means effective under one condition to actuate the lock without releasing said interlocking means, and effective under another condition to release said interlocking means to permit the removal of the lock from the closure, so that the ordinary key and the master key, while effective to actuate the lock or a number of locks of a master system, respectively, are ineffective to release the interlocking means, thus necessitating the use of a super-master key which is effective to actuate the lock and also to release the interlocking means so the cylinder may be removed from the closure by one possessing the super-master key and, therefore, presumably authorized to remove said lock from the closure.

The above objects of the invention and other objects ancillary thereto will best be understood from the following description considered with reference to the accompanying drawing forming a part of the present specifications.

In the drawing:

Fig. 1 is a rear view of a pin tumbler cylinder in a lock case on a closure;

Fig. 2 is a sectional view on the line 2—2 of Fig. 1, showing a super-master key inserted within the key plug and the pin tumblers positioned thereby so that the key can actuate the lock and also release the interlocking means;

Fig. 3 is a sectional view on the line 3—3 of Fig. 2;

Fig. 4 is a view partly in section of the key plug and associated parts of the present construction, showing the ordinary key effective to actuate the lock, but ineffective to release the interlocking means;

Fig. 5 is a detail plan view of an interlocking member;

Fig. 6 is a fragmentary top plan view of the key plug and associated parts.

Referring to the drawing in detail, there is shown a lock comprising a pin tumbler cylinder 10 threaded into an opening 12 provided in the usual lock case 14, mounted within a door or other closure 16. The cylinder 10 is provided with the usual rotatable key plug 18, pin tumblers 20, and the usual lock or latch bolt actuating member 22. Said member 22 is secured at the inner end of the key plug 18 by screws 24, and thus prevents removal of the key plug from the cylinder case.

In accordance with the present invention, means are provided to interlock the cylinder case 10 with the lock case 14 to prevent rotation of the cylinder case 10 with respect to the lock case 14 and thereby to prevent the cylinder from being unscrewed from the lock case and removed from the closure. For this purpose the lock case is provided with a slot or recess 26 into which the interlocking member, here shown as a dog 28, may be projected. The dog 28 is slideable within a groove 30 extending transversely in said cylinder and is provided with a rack 32 adapted to mesh with a gear tooth section 34 provided on an annular gear member 36. Said gear member surrounds the key plug 18 and is mounted for rotation within a peripheral groove 38 provided in the cylinder 10. The gear sleeve 36 is provided with a forwardly extending projection 40 adapted to be engaged by a rearwardly extending projection 42 on a sleeve 44 which surrounds the key plug 18 and which is mounted for rotation within the peripheral groove 38 in the cylinder 10.

Said sleeve 44 is provided with openings for additional pin tumblers 46 which, as illustrated

in Fig. 4, are normally so positioned that the breaks therein are at the outer surface of said key plug so that said key plug is normally free to rotate independently of the sleeve 44 and the gear member 36 when an ordinary key or even when an ordinary master key is used for actuating the lock. When, however, a special or super-master key is inserted within the key plug, as illustrated in Fig. 2, the pin tumblers 46 are raised by the key and interlock the sleeve 44 with the key plug 18. When said sleeve 44 is thus interlocked with the key plug 18, rotation of the latter also effects rotation of the sleeve 44 and as the result of the engagement of the projection 42 with the projection 40 on the gear member 36, the latter is caused to rotate and thereby move the dog 28 into and out of the recess 26 depending upon the direction of rotation thus interlocking the cylinder case 10 with the closure 16 or releasing said interlock, respectively. In practice, when the locks constructed in accordance with the present invention are installed in the doors or other closures, the cylinders 10 are screwed into the openings 12 and, by use of the super-master key 48, the end tumblers 46 are caused to interlock the sleeve 44 with the key plug 18, so that rotation of the key plug by the super-master key 48, in a clockwise direction, is effective to project the interlocking member or dog 28 into the slot or recess 26. When said key 48 is removed from the key plug 18, and an ordinary key 50 is inserted, the breaks in the pin tumblers 46 are then automatically positioned at the outer surface of the key plug and, in that case, the key plug 18, when rotated within the cylinder, is ineffective to rotate the sleeve 44 either clockwise or counter-clockwise, and is therefore ineffective to retract the locking member 28 from the slot 26. When the dog is projected into the slot 26 in the case 14, the cylinder 10 cannot be rotated with respect to said lock case, and it is therefore impossible to unscrew said cylinder from the closure. Also, since the lock case 14 is threadedly engaged by the cylinder, it is impossible to remove the lock case from the closure in which it is mounted. It will be understood that the lock is so designed that the ordinary key and the ordinary master key, such as the key 50, of a master lock system are effective to actuate the lock, but are ineffective to actuate the interlocking member or dog 28, either to project or retract the latter, and that said interlocking member can be actuated only by the use of a super-master key, such as the key 48, which will be under the control of one authorized to remove or install such locks.

As illustrated in Fig. 6, the projection 42 of the sleeve 44 is positioned so that it is necessary to rotate said sleeve substantially one complete revolution before said projection engages the projection 40 on the gear member 36, and thereby becomes effective to move said gear member to project the dog into the recess. When the dog is thus projected and the super-master key is withdrawn from the key plug, the tumbler pins are forced down by the driver pins and interlock the key plug 18, the sleeve 44, and the cylinder, thereby to prevent forcing of the dog out of the recess in the closure. When the ordinary key or ordinary master key is used to actuate the lock, the tumbler pins 46 as well as the tumbler pins 28 are raised so that their breaks occur at the outer surface of the key plug 18 and thus permit rotation of the key plug to actuate the lock

without, however, actuating the sleeve 44 which remains locked to the cylinder 10 by the driver pins. In order to withdraw the dog from its recess when the key plug is actuated by the super-master key, the sleeve 44 clutched to said key plug is rotated substantially one complete revolution in the opposite direction before the projection 42 engages the projection 40 on the gear member 36 and thereby becomes effective to actuate said gear member to withdraw the dog from the closure recess 26, and when the super-master key is withdrawn, the lock is in normal position to be removed from the closure by merely unscrewing the cylinder.

Thus it is seen that the construction herein shown and described is well adapted to accomplish the several objects of the present invention. It will be understood, however, that the present construction may be varied and that the invention may be embodied otherwise than as here shown. Therefore, I do not wish to be limited to the precise constructions herein disclosed, except as may be required by the appended claims and the prior art.

Having thus described my invention, what I desire to secure and claim by Letters Patent of the United States is:

1. In a pin-tumbler lock, a pin-tumbler cylinder, a key plug rotatable in said cylinder, a dog mounted in said cylinder for movement transversely thereof, said dog having a rack, a rotatable gear sleeve in mesh with said rack, a rotatable pin tumbler sleeve adapted to engage said gear sleeve normally inoperative by said key plug but effective under a predetermined condition to be rotated thereby for engaging said gear sleeve in order to rotate the latter and thereby move said dog.

2. In a pin-tumbler lock, a cylinder, a key plug rotatable in said cylinder, a sleeve surrounding said key plug and also rotatable in said cylinder and provided with a projection, a gear member surrounding said plug rotatable within said cylinder and provided with a projection adapted to be engaged by said sleeve projection, said plug being normally rotatable independently of said sleeve and gear, means operative to clutch said sleeve to said plug to rotate said sleeve when the plug is rotated, thereby to engage said sleeve projection with said gear projection and rotate said rack, and a dog mounted on said cylinder for movement transversely thereof provided with a rack in mesh with said gear whereby actuation of said sleeve is effective to move said dog with respect to said cylinder.

3. In a pin-tumbler lock, a pin-tumbler cylinder, a key plug rotatable in said cylinder, a dog mounted in said cylinder for movement transversely thereof, said dog having a rack, a rotatable gear sleeve in mesh with said rack, a rotatable pin tumbler sleeve adapted to engage said gear sleeve normally inoperative by said key plug but effective under a predetermined condition to be rotated thereby for engaging said gear sleeve in order to rotate the latter and thereby move said dog, said pin-tumbler sleeve having a lost motion connection with said gear member and effective, after actuation by said key plug to rotate the gear member in one direction to move the dog, to remain in position to prevent movement of the gear member in the opposite direction until the key plug is rotated a predetermined amount in said opposite direction.

HAROLD MACHINIST.
